CLAIM

The ornamental design for a vehicle wheel, as shown and described.

DESCRIPTION

FIG. 1 is a perspective view of a vehicle wheel according to our design;

FIG. 2 is a front view of the vehicle wheel; and,

FIG. 3 is a left side view of the vehicle wheel, the right side view being a mirror image. The top and bottom views being the same as the side views.

In the drawings the broken lines depict environmental subject matter and form no part of the claimed design.
